HARRY V. BALL, OF CONCORD, MASSACHUSETTS, ASSIGNOR TO R. HOE & CO., INC., OF NEW YORK, N. Y., A CORPORATION OF NEW YORK.

WEB-ROLL CONTROLLING MECHANISM.

Application filed May 15, 1926. Serial No. 109,242.

This invention relates to certain improvements in methods of joining or splicing a running web to a spare roll of paper for web renewal in printing machines.

5 In modern high speed printing press operation in which a large number of copies are to be run off the press, the paper webs have to be renewed during the press run. Time is, of course, of the highest importance in press 10 operation and it is desirable that the operation of the press shall be interfered with to the least possible degree during this web renewal. Various efforts have been directed toward the production of a so called flying 15 paster, that is, the renewing of the web without stoppage of the press. In these flying pasters it is necessary in making the splice that the spare roll be moved or rotated before the splice or paste is made, as these 20 rolls are heavy and the weight of the roll could not be picked up if the paste were made with a moving web and a stationary roll.

It is a special object of the present invention to provide an improved method for web 25 renewal by the practice of which the spare roll is given an initial rotary or turning movement prior to the making of the splice and in which no special mechanism is required for thus initially starting the roll.

It is a further object of the invention to provide an improved method for bringing the web and the spare roll into surface engagement for effecting the splice.

35 With these and other objects not specifically referred to in view, the invention consists broadly in effecting a relative movement of the spare roll and the running web so as to bring them into surface engagement, this engagement being of such character that the spare roll is rotated solely by the engagement therewith of the running web, so that no mechanism for effecting the initial rotation of the roll is necessary. 40 The improved method may, of course, be carried out by various apparatus, and one such apparatus is shown in the accompanying drawings, in which

Figure 1 is one view of an arrangement 50 for supporting a spare roll and a running roll by which the surface engagement of the web and the roll is effected, the web being shown in contact with the spare roll, and

55 Figure 2 is a view similar to Fig. 1 showing the roll moved to running position after

the splice has been made and a new spare roll brought into position, the spare roll being shown in dotted lines.

In the particular application of the method shown, the surface engagement of the running web and the spare roll is effected by so arranging the running roll and the spare roll that the running web is brought into contact with the spare roll while running in substantially its normal feeding path, this feeding path of the web shifting as the roll decreases in size, so that when the running roll is near depletion the web path is tangent to the surface of the running roll and the web is in surface contact with the roll. By this means the web is automatically moved toward the spare roll and no mechanism is required for shifting the web into engagement with the spare roll, so that danger of web breakage from such cause is avoided. Furthermore, the web gradually contacts with the spare roll, thereby starting the rotation of the roll easily, the pressure of the web gradually increasing and increasing the speed of rotation of the roll.

80 Where the surface engagement of the spare roll and the running web is thus effected, the roll support will include suitable supporting frames 1 which support the necessary mechanisms. But one side of the apparatus is shown, it being understood that the construction is duplicated on each side of the machine. The side frames 1 support brackets 3 having top rails 4 on which the spindles 5 of the spare rolls are adapted to 85 run, the spare rolls being loaded in any suitable manner onto these brackets, this being the loading position of the roll and the point at which the splice is made. The rolls move along these rails 4 by gravity and the rails are, therefore, slightly inclined from the horizontal, as shown. The spare rolls S, one of which is shown, are held in reserve position at the right-hand end of the brackets until after the splice is made and are 90 then moved to a running position, as hereinafter referred to. To hold the spare roll in position, a stop is provided in the form of a pivoted segment 6 supported on a rock shaft 7 mounted in the brackets 3, before 95 referred to, this segment being provided with a nose 8 which bears against the roll spindle. This segment is rocked out of the way by any suitable mechanism, not illustrated, it being unnecessary for an under- 100 105 110

standing of the present invention. After the splice is made, the roll is moved to a running position, and in the particular apparatus shown the roll is moved by gravity 5 to a running support, shown as rocking bearings 9 in brackets 10 suitably supported to the side frames 1. These bearings are, as shown, supported below and to one side of the point of support of the reserve roll, the 10 position of these lower bearings being so laid out that as the running roll, indicated by R, is about to become depleted the path of the web is such as to bring it against the spare roll, as shown in Fig. 1.

15 The spare rolls are supported on the tracks so that they are freely rotatable, and the surface engagement of the web with the roll causes the rotation of the spare roll on its support, so that the required initial rotation of the roll is given by the web without the necessity of manipulating the web in any way, or providing any mechanism for starting the roll.

It will be further observed that no backing is necessary for effecting the splice, the roll and the web being clear of any mechanism at the point the splice is made. In practicing the method, paste or other suitable adhesive is applied to the end of the 25 new roll, which is turned so as to bring the pasted portion to or approximate to the point marked X in Fig. 1, so that the spare roll will have almost a full rotation (in the direction of the arrow) before it is picked up by the web. In carrying out the method, when the running roll is nearly expired, the press is preferably slowed down so that the web is running slowly at the time it comes into contact with the spare roll. The 30 engagement of the web with the roll rotates the roll until the point at which the adhesive has been applied comes into contact with the web. At this time the pressure of the web against the roll is sufficient to cause the 35 web to affix itself to the end of the spare roll and the two webs go off together. After the splice has been made, the old web may be broken in any suitable manner, as by a wire or stick, and the press again accelerated up to speed.

The spare roll may be moved from the reserve position to the running position in any suitable manner, as by blocks 11, which control the downward movement of the roll 40 to the bearings 9, the movement of these blocks being controlled in any suitable manner from cables 12 operated by mechanism not shown, as being unnecessary for an understanding of the invention. During the 45 downward movement of the spare roll the bearings 9 may be rocked to discharge the spindle of the expired roll R.

If desired, means such as belts 13, supported in suitable swinging frames 14 may be 50 employed for controlling the running speed

of the roll. But these belts are not essential for carrying out the method of the present invention and may be omitted if desired, and other means for securing the desired tension on the running web may be used. It will be 70 seen that the belts act to maintain the desired tension on the unwinding web, as in the case of the more common brakes on the roll shaft. The pressure of the belts on the roll, the resulting tension on the running web, 75 and the arrangement of the expiring web with respect to the new roll are maintained during the splicing operation, as shown in Fig. 1, and the engagement of the web with the new roll is sufficient for rotating the 80 latter. The tension on the running web may be regulated in various ways, as by increasing the weight of the belt carrying arms 14, or by the use of suitable devices for causing the belt arms to exert different degrees of 85 pressure on the running roll. It will be seen that, in the construction shown, there is or may be no braking or other tension producing effect on the new roll until the splice is made and the new roll started towards 90 its running position, so that the new roll is free to be started into rotation by the running web, and, especially with the ball or roller bearings now used for such web rolls, a very small pressure of the running 95 web is sufficient to start the new roll, even without any assistances from the operator.

The running web is indicated by W, and passes to the press, not shown, over a guide roll 15 carried in adjustable arms 16 on a 100 shaft 17 suitably supported in brackets 18 secured to the machine frame.

It will be seen that with the method described a very simple and effective method of web renewal is secured for effecting the 105 initial rotation of the spare roll and the splice, and mechanism for effecting the movement of the web into pasting position is eliminated, and a splice may be made without stopping the press. While the 110 method for effecting surface engagement of the roll and the web is a very convenient one, it will be understood that the method broadly considered is not to be restricted to this step, but that other ways of effecting 115 this engagement may be used in practicing the method.

What I claim is:

1. The method of joining or splicing a running web which is feeding to the press 120 with a spare roll of paper, which consists in supporting the spare roll so as to be freely rotatable in its bearings, applying a suitable adhesive to the surface of the spare roll, effecting a relative movement of the spare 125 roll and the running web so as to bring them into a surface engagement sufficient to cause the rotation of the spare roll solely by the engagement therewith of the running web, and maintaining this engagement until the 130

gummed surface of the spare roll contacts with the web and makes the splice.

2. The method of joining or splicing a running web which is feeding to the press

- 5 with a spare roll of paper, which consists in supporting the spare roll so as to be freely rotatable in its bearings, applying a suitable adhesive to the surface of the spare roll, slowing down the press, effecting a relative movement of the spare roll and the running web so as to bring them into a surface engagement with gradually increasing pressure sufficient to cause the rotation of the spare roll solely by the engagement therewith of the running web, maintaining this engagement until the gummed surface of the spare roll contacts with the web and makes the splice, and bringing the press up to speed.

- 20 3. The method of joining or splicing a running web which is feeding to the press with a spare roll of paper, which consists in supporting the spare roll so as to be freely rotatable in its bearings, applying a suitable adhesive to the surface of the spare roll, effecting a relative movement of the spare roll and the running web so as to bring them into a surface engagement sufficient to cause the rotation of the spare roll solely by the engagement therewith of the running web, maintaining this engagement until the gummed surface of the spare roll contacts with the web and makes the splice, breaking off the expiring web, and shifting the new roll from splicing position to a running position.

4. The method of joining or splicing a running web which is feeding to the press with a spare roll of paper, which consists in supporting the spare roll so as to be freely rotatable in its bearings, applying a suitable adhesive to the surface of the spare roll, slowing down the press, effecting a relative movement of the spare roll and the running web so as to bring them into a surface engagement sufficient to cause the rotation of the spare roll solely by the engagement therewith of the running web, maintaining the engagement until the gummed surface of the spare roll contacts with the web and makes the splice, breaking the expiring web, shifting the new roll from splicing position to running position, and bringing the press up to speed.

- 55 5. The method of joining or splicing a running web which is feeding to the press with a spare roll of paper, which consists in supporting a spare roll and a running roll so arranged that on the depletion of the running roll the web therefrom is brought into a surface engagement with the spare roll sufficient to cause the rotation of the spare roll solely by the engagement therewith of the running web, applying a suitable adhesive to the surface of the spare

roll, and maintaining the engagement of the web and spare roll until the gummed surface of the spare roll contacts with the web and makes the splice.

6. The method of joining or splicing a running web which is feeding to the press with a spare roll of paper, which consists in supporting a spare roll and a running roll so arranged that on the depletion of the running roll the web therefrom is brought into a surface engagement with the spare roll sufficient to cause the rotation of the spare roll solely by the engagement therewith of the running web, applying a suitable adhesive to the surface of the spare roll, slowing down the press, maintaining the engagement of the web and spare roll until the gummed surface of the spare roll contacts with the web and makes the splice, breaking off the expiring web, and bringing the press up to speed.

7. The method of joining or splicing a running web which is feeding to the press with a spare roll of paper, which consists in supporting a spare roll and a running roll so arranged that on the depletion of the running roll the web therefrom is brought into a surface engagement with the spare roll sufficient to cause the rotation of the spare roll solely by the engagement therewith of the running web, applying a suitable adhesive to the surface of the spare roll, slowing down the press, maintaining the engagement of the web and spare roll until the gummed surface of the spare roll contacts with the web and makes the splice, breaking off the expiring web, shifting the new roll from splicing position to running position, and bringing the press up to speed.

8. The method of joining or splicing a running web which is feeding to the press with a spare roll of paper, which consists in supporting the spare roll so as to be freely rotatable in its bearings, applying a suitable adhesive to the surface of the roll, effecting a relative movement of the spare roll and the running web so as to bring them into a surface engagement sufficient to cause the rotation of the spare roll solely by the engagement therewith of the running web, maintaining the running roll under the control of pressure devices while the splice is being made, continuing the engagement of the spare roll and the running web until the gummed surface of the spare roll contacts with the web and makes the splice, and then effecting the movement of the new roll into the control of pressure devices for controlling its unwinding.

9. The method of joining or splicing a running web which is feeding to the press with a spare roll of paper, which consists in supporting the spare roll so that it may rotate in its bearings, applying a suitable adhesive to the surface of the roll, causing

the spare roll and the running web to engage with a surface contact sufficient to cause the rotation of the spare roll solely by the engagement therewith of the running web, 5 and maintaining this engagement until the gummed surface of the spare roll contacts with the web and makes the splice.

10. The method of joining or splicing a running web which is feeding to the press 10 with a spare roll of paper, which consists in supporting the spare roll so as to be freely rotatable in its bearings, applying a

suitable adhesive to the surface of the spare roll, effecting a relative movement of the spare roll and the running web and bringing them into surface engagement, rotating the spare roll, and maintaining the rotation of the spare roll by the engagement therewith of the running web until the splice is made and the web is advanced by the pull 20 thereon.

In testimony whereof, I have hereunto set my hand.

HARRY V. BALL.
